(Cl. D26—1)

To all whom it may concern:

Be it known that I, Raymond J. Breckheimer, a citizen of the United States and resident of Milwaukee, in the county of Milwaukee and State of Wisconsin, have invented a new, original, and ornamental Design for an Air Filter for a Welding Generator, of which the following is a specification, reference being had to the accompanying drawing, forming part thereof.

Figure 1 is a side elevational view of an air filter for a welding generator showing my new design.

Figure 2 is a front elevational view of the filter.

I claim:

The ornamental design for an air filter for a welding generator, as shown.

RAYMOND J. BRECKHEIMER.
